United States Patent Office.

ASAHEL TODD, JR., OF PULTNEYVILLE, NEW YORK.

Letters Patent No. 97,834, dated December 14, 1869.

IMPROVEMENT IN TICKET-BOXES FOR RAILROAD PASSENGER-TRAINS.

The Schedule referred to in these Letters Patent and making part of the same.

To all whom it may concern:

Be it known that I, ASAHEL TODD, Jr., of Pultneyville, Wayne county, New York, have invented new and useful Improvements in the Collection of Fares upon Railroad Passenger-Cars; and I do hereby declare that the following is a full, clear, and exact description thereof, reference being had to the accompanying drawings, making a part of these specifications, in which—

Figure 1 is a perspective view of a metallic shield and receptacle for holding and discharging a ticket or coupon.

Figure 2 is the reverse side of the same, showing the works connected therewith.

Figure 9 is a section of figs. 1 and 2.

The metallic shield A may be cast from brass or malleable iron, or pressed from sheet-metal, and is provided with parallel grooves cast or punched through the face of the shield, to allow the movable platforms D D and G G to pass freely through.

B, fig. 1, is a metallic table or shelf, secured to the face of the shield, or it may be fastened upon the panel of the car, directly under the shield.

C C', and cross-sections a a, fig. 1, are the metallic frame of the receptacle, which is provided with a groove in the inner edge of C C', to retain the glass E E.

The cross-sections should be thick enough to allow the ticket to pass freely through between the glass and shield.

The inverted hollow cone F, fig. 1, is provided with a channel for slides, H H, and is secured to the shield by a thread and screw, or by rivets.

b b, fig. 1, are sockets cast upon the rim of the shield, to secure the hinged lever I.

The hinged lever I and platform D, may be cast in one piece of metal. There should be sufficient curve to the lever I to bring the platform D D against the glass E E, and to rest upon the inverted cone, as in fig. 2.

The cone J may be cast or riveted upon the lever I.

The spring-lever and platforms G, Figures 5 and 2, are made by riveting springs of steel or brass upon the lever G and posts d d.

Figure 7 is a bar, with two pins attached of sufficient length to pass through the holes c c" when the bar is secured to the rim of the shield, and to retain the spiral springs coiled around the pins.

S S, fig. 6, are springs with combined slides H and catch N attached.

The springs are riveted to the inner side of the rim of the shield A, in such a position as to allow the slides H to pass freely through the channel in the inverted cone F, and to permit the catches N to clasp the hinged lever I.

A', fig. 3, is a key, with a triangular box, K L, to hold the coupon-tickets.

The key A' has a recess in the end, corresponding with the cone J, and is provided with a handle, f.

The box K L, fig. 3, is made by bending each end of the plates K and L at right angles with the plates K and L, and pivoting them in the centre of each end by a pin.

The ends should be rounded from the centre to the edge of the plates, to allow the under part of the box to close, and is kept closed by means of a spiral spring attached to L at l, fig. 3.

M is a spiral spring coiled around the key, and is secured by a shoulder turned at the proper distance from the end, to insure the movement of the box when the key is pressed against the cone J.

The ticket, Figure 8, represents an ordinary railroad-ticket, with a coupon attached, representing, by figures, the number of the station for which the ticket has been purchased.

The small figures are the number of the ticket, and should be printed upon both sections, or the number of the ticket may be printed at the point where the two tickets join.

The coupon should be nearly severed from the ticket by cutting, punching, or by indentations upon the card, so it may be readily severed from the ticket.

To enable others to make and use my invention, I will explain the construction and manner of operating the same.

Fasten the receptacle to the shield by screws or rivets, slide the glass E E into the groove, and secure the same by a pin or screw. Fasten the inverted cone to the shield by rivets, or a thread-screw may be cut upon the cone and shield.

The table B may be fastened to the shield, or upon the panel of the car, directly under the receptacle.

The hinged lever I should be pivoted to the sockets B B at the proper point to allow the platform D D to pass through the groove in the shield, and to bring the cone J in the centre of the key-hole.

The spring, slide, and catches n n are riveted to the rim of the shield, in such a position as to permit the slides to pass freely through the channel in the inverted cone, and to hold firmly, by the catches, the hinged lever when the key is not in use.

Secure the bar O, fig. 7, directly over the platform D, so that the spiral springs and guides will act above and through the holes c c" in the hinged lever I.

Rivet, or secure by screws, the springs P P to the lever and platforms G G, and to the posts D' D'.

Secure the shield to the panels of the car, between the windows, high enough to bring it even with the shoulder of a man when standing in the aisle.

The key A', fig. 3, should be long enough to reach the inverted cone by a person standing in the aisle, or passage between the seats.

The triangular box must move easily upon the key, and should be shorter than the receptacle in the shield.

Stations on all railroads are numbered from its principal terminus; as, for instance, Albany, New York, is station No. 1 on the New York Central Railroad; the next station west would be No. 2.

I print in prominent figures, upon the coupon attached to the ticket, a number corresponding with the number of the station for which the ticket has been purchased.

The seats in the cars should be divided by an arm in the centre, making two distinct seats.

When the conductor enters the car, he will observe if there are coupons in the receptacles; if not, will receive from the passenger his ticket, fold the coupon over upon the ticket, and punch through both. Returning the ticket to the passenger, he will place the coupon for the right-hand passenger in the right-hand division of the triangular box; the coupon for the left-hand passenger, in the left-hand division; then insert the key in the key-hole, which will press the upper side of the plate L back, and allow the coupon to fall through to the platform D, figs. 4 and 2. Continuing the pressure will move the slides H and hooks N N, which releases the hinged lever I. The key then presses against the cone J, pushing back the platform D, which permits the coupon to fall into the receptacle. Withdraw the key, and the springs b' b", fig. 7, force the platform back to its place.

Should a passenger desire to change his seat, he will press against the spring-lever at c' c", which will allow his coupon to fall upon the shelf B, and may be placed in another receptacle by the conductor.

Should a passenger fail to obtain a ticket before entering the cars, there should be an office in the rear car, where he may obtain one.

Before arriving at the station for which the ticket has been purchased, the coupon should be dropped, and the ticket secured by the conductor.

If a passenger wishes to stop off before arriving at the station for which his ticket has been purchased, a double punch, and number of the station made with a pencil, will allow him to resume his journey from that station at any subsequent time. To assist the conductor in using the ticket as a stop-off ticket, the numbers of the principal stations should be printed upon the margin of the ticket. The shield behind the glass being painted black, the punch-mark is distinctly seen, and the same punch should be sent over the entire line, but should not follow upon the same train at regular periods.

As all the tickets sold upon the train are charged to the conductor, and must be accounted for, and as all tickets can be secured by the conductor, this system effectually prevents fraud upon the railroad company, either by conductors or passengers.

What I desire to secure by Letters Patent, is—

1. The self-closing receptacle C E, attached to the case A, for holding in view a coupon or ticket, its insertion being under the control of the conductor, and its removal under the control of the passenger or conductor.

2. The arrangement of the conical recess F, in the case A, the hinged lever I, and gate D, for admitting the coupon, together with the spring-levers G G, for releasing the same.

3. The key A', having a triangular spring-box, K L, for the insertion of the coupon into the receptacle.

4. In combination with the ticket-box, as constructed, the employment of the coupon-ticket as described, substantially and for the purposes set forth.

ASAHEL TODD, Jr.
